UNITED STATES PATENT OFFICE.

GILBERT SORENSEN, OF CASSELTON, NORTH DAKOTA.

FLUE-CUTTER.

No. 870,800.

Specification of Letters Patent.

Patented Nov. 12, 1907.

Application filed March 23, 1907. Serial No. 364,077.

To all whom it may concern:

Be it known that I, GILBERT SORENSEN, a citizen of the United States, residing at Casselton, in the county of Cass and State of North Dakota, have invented certain new and useful Improvements in Flue-Cutters, of which the following is a specification.

This invention contemplates certain new and useful improvements in tools for cutting boiler flues and the invention has for its object a cheap, simple and efficient construction of tool of this character which will enable the operator to stand on the outside of the fire box and accomplish the desired work instead of being compelled to operate from the inside, where the cramped position will materially interfere with the work.

The invention consists in certain constructions, arrangements and combinations of the parts which I shall now hereinbelow fully describe and then point out the novel features in the appended claims.

For a full understanding of the invention and the merits thereof and also to acquire a knowledge of the details of construction of the means for effecting the result, reference is to be had to the following description and accompanying drawings, in which:

Figure 1 is a perspective view of my improved flue cutter; Fig. 2 is a longitudinal sectional view thereof; Figs. 3 and 4 are transverse sectional views, the cutter being shown in different positions in the respective views; Fig. 5 is a transverse sectional view on the line 30 5—5 of Fig. 2; and, Figs. 6, 7 and 8 are detail perspective views of the types of cutters that may be employed.

Corresponding and like parts are referred to in the following description and indicated in all the views 35 of the drawings by the same reference characters.

Referring to the drawings, the numeral 1 designates the stock of my improved flue cutting tool, the same being designed to fit loosely within a flue and being formed at a point intermediate of its ends with a circular eccentrically positioned socket 2 with which a 40 segmental slot 3 communicates, the said slot extending radially, as shown.

Each cutter for the tool is provided with a circular shank or head 4 adapted to fit in the circular socket 2 and provided with a marginal recess 5 by which it may pass the somewhat contracted mouth of the socket 2, as it is inserted therein through the slot 3. After being inserted in the socket, the cutter is prevented from becoming accidentally disengaged therefrom in 45 the cutting operation, as the cutter can only be detached from the socket and inserted therein when the recess 5 registers with one side of the contracted mouth of the socket. When in operation the cutters will be turned so as to lie against one side wall of the slot 3, in 50 which position the said marginal recess 5 will be out of registry with the contracted mouth of the socket

and the cutter will thus be securely held in place. The stock 1 is provided with non-circular end sockets 1^a in which the bars 7 and 8 fit and in which they are secured by means of taper pins or keys 9. One of these bars 5 is sufficiently long to extend through the flue that is intended to be cut, while the other is relatively short. On the first named bar a washer 10 is adapted to fit under certain conditions of service, in which event also there is a spring 11 back of the washer and encircling the bar, a follower 12 is slidably mounted on the bar back of the spring and bearing thereagainst and formed with oppositely extending studs 13, said studs being adapted for engagement by an eccentric 14 on the forked lever 15 which is fulcrumed on a collar 16 60 adjustably held on the bar by means of a set screw.

In the present instance I have shown three different forms of cutters designated A, B and C. The cutter A is designed to cut the flue on the inside of the boiler and is of such a length that its pointed cutting end 17 75 will project from the stock 1 when the latter is turned in one position to cut the flue, the cutter resting against one side wall of the slot 3 whereas when the stock is turned in the opposite direction, the said cutter will lie against the opposite wall of the stock substantially 80 flush with the surface of the stock, so as to in no wise interfere with the insertion and withdrawal of the tool in and from the flue, it being remembered that the socket 2 is eccentrically located with respect to the socket.

The cutter B is designed to cut the bead of the flue and is provided with a recessed and beveled cutting edge 18 which will prevent the tool from cutting any farther than to the flue sheet, because the point of the tool which extends outside of the flue is ground off 90 round away from the flue sheet and therefore will not damage the same. In the practical operation of this cutter, the stock is first slipped through the flue, the cutter is then slipped into place, the washer 10 is slipped over the longer bar and lies against the flue 95 sheet. The coiled spring is then placed on the bar back of the washer and the other intermittent parts are properly positioned and the eccentric lever is turned towards the flue sheet so as to give the proper tension on the spring and cause the tool in the fire box end of the 100 flue to cut the bead off when the tool is given one turn by means of power applied to the relatively short bar.

The cutter C is designed to cut a new flue the exact length required, and this is accomplished in the same manner as in cutting off the bead. In connection 105 with the cutter C, it is to be noted that it is formed with a cutting edge 19 and an offset end 20 which latter forms a guide adapted to ride upon the outer face of the flue sheet. Hence, the cut will be formed according to the flue sheet and not necessarily straight around 110 the flue, this feature being obviously of great importance with a crooked flue sheet.

It is manifest that when the flue is cut at the front end the tool is reversed and the bars also reversed, the tool being turned to the left instead of to the right as in the foregoing operation.

5 From the foregoing description in connection with the accompanying drawings, it will be seen that I have provided a very simple, durable and efficient construction of flue cutter which will wear a long time, as there are no parts to wear out except the cutters and as 10 they are removable, they may be easily ground and replaced, or new ones may be easily made and substituted for the old ones. Furthermore the cutters themselves may be manufactured so cheaply that a plurality of sets may be sold with the one tool.

15 Having thus described the invention, what is claimed as new is:

1. A flue cutter, embodying a stock formed with an eccentrically located socket and a segmental slot communicating therewith, the socket being provided with a contracted mouth leading from the slot, and a cutter provided with a round head adapted to fit in said socket and formed with a marginal recess and adapted to register with the contracted mouth so as to permit the cutter to be slipped in and withdrawn from the socket.

20 2. A flue cutting tool, embodying a stock and a cutter secured thereto, said cutter being provided with an offset and angularly disposed end adapted to form a guide resting against the end of a flue in the cutting operation, as and for the purpose set forth.

25 3. A flue cutting tool, comprising a stock adapted to fit within the flue, a cutter secured to said stock, end bars se-

cured to said stock, one of said bars being adapted for use in turning the stock, a washer adapted to fit on the other bar, a spring encircling said bar and adapted to bear against said washer, a follower slidably mounted on the bar back of the spring and bearing thereagainst, and an eccentric lever fulcrumed on the bar and adapted to bear against said follower to force it against the spring.

4. A flue cutting tool, comprising a stock adapted to fit within the flue, a cutter secured to said stock, end bars secured to said stock, one of said bars being adapted for use in turning the stock, a washer adapted to fit on the other bar, a spring encircling said bar and adapted to bear against said washer, a follower slidably mounted on the bar back of the spring and bearing thereagainst, and an eccentric lever fulcrumed on the bar and adapted to bear against said follower to force it against the spring, 40 follower being formed with oppositely extending studs and the eccentric lever being formed with two members bearing against said studs.

45 5. A flue cutting tool comprising a stock adapted to fit within a flue, a cutter secured to said stock, bars secured to the ends of said stock, a washer slidably mounted on one of said bars, a spring encircling the bar back of the washer, 50 a follower slidably mounted on the bar back of the spring and provided with oppositely extending studs, a collar mounted on the bar back of the follower and adapted to be held at different adjustments on said bar, and a forked eccentric lever fulcrumed on said collar and provided with two eccentrics engaging said studs.

55 In testimony whereof I affix my signature in presence of two witnesses.

GILBERT SORENSEN. [L. S.]
